CLAIM

The ornamental design for a combined electronic artificial larynx and neck cord, as shown and described.

DESCRIPTION

FIG. 1 is a top perspective view of a combined electronic artificial larynx and neck cord, showing my new design;

FIG. 2 is a top plan view thereof, with the neck cord truncated for ease of illustration;

FIG. 3 is a bottom plan view thereof;

FIG. 4 is a right side elevational view thereof;

FIG. 5 is a left side elevational view thereof;

FIG. 6 is a front elevational view thereof; and,

FIG. 7 is a back elevational view thereof.

FIG. 1

FIG. 2

FIG. 3

FIG. 4
